UNITED STATES PATENT OFFICE

JOSEPH KOBERLING, OF SAN FRANCISCO, CALIFORNIA

FIREPLACE DAMPER CONSTRUCTION

Application filed July 26, 1932. Serial No. 624,859.

This invention relates to certain new and useful improvements in fireplace damper construction.

The primary object of the invention is to provide a fireplace damper capable of mounting in vertical or angularly arranged flue or chimney passages with a universal connection in the operating mechanism for the damper permitting different angular 10 mountings of the damper in the flue or chimney passageway.

A further object of the invention is to provide a fireplace damper and operating mechanism therefor wherein the operating 15 mechanism includes an adjustable flame structure to accommodate the mounting of the operating mechanism on the rear or back key stone of a fireplace arch.

With the above and other objects in view 20 that will become apparent as the nature of the invention is better understood, the same consists in the novel form, combination and arrangement of parts hereinafter 25 described, shown in the accompanying drawings and claimed.

In the drawings:—

Figure 1 is a vertical cross-sectional view 30 of a fireplace and associated flue with the damper set in the base of the flue at the head of the fireplace with the operating mechanism for the damper located at the fireplace arch and showing by dotted lines the damper mounted in an angularly disposed flue;

Figure 2 is a vertical cross-sectional view 35 of a fireplace and associated flue, similar to Figure 1, with the damper set into the lower end of the flue at the head of the fireplace and the operating mechanism horizontally aligned with the damper above the fireplace 40 mantel;

Figure 3 is a detail sectional view taken 45 on line 3—3 of Figure 2, showing the connection between the operating rod and damper;

Figure 4 is a top plan view of the damper operating mechanism and supporting structure therefor with the link connecting the operating mechanism to the damper shown in section;

Figure 5 is a vertical longitudinal sec-

tional view taken on line 5—5 of Figure 4, showing the adjustable frame carrying the damper operating mechanism;

Figure 6 is an outer end elevational view 55 of the supporting frame for the damper operating mechanism; and

Figure 7 is a cross-sectional view taken 60 on line 7—7 of Figure 4, showing the universal connection in the damper operating mechanism for the link rod connection between said mechanism and damper.

Referring more in detail to the accompanying drawings, and particularly to Figures 1 and 2, there is illustrated a fireplace comprising a rear wall 10, an upper front 65 wall 11 spaced by a mirror or other ornamental finish 12 above the mantel 13 with the fireplace opening 14 disposed below the mantel and backed by the fire arch 15. The open upper end of the fireplace 14 is in 70 communication with a chamber 16 leading to the vertical chimney passageway or flue 17.

The damper 18 is pivotally supported 75 between the chamber 16 and flue 17 above the mantel 13 as shown in Figure 1, by means of pivot pins 19 having pivot bearings in angle strips 20 set into the rear and front wall constructions 10 and 11 of the fireplace.

The operating mechanism for the damper 80 18 as shown in detail in Figures 4 to 7 includes an adjustable frame 21 mounted upon the rear or back key stone 22 as shown in Figure 1, rearwardly of the key stone 23 above the fireplace opening 14, the adjustable frame including an inverted U-shaped strap having an upper cross bar 24 carrying depending side legs 25 engaged with the upstanding side legs 26 of a U-shaped member including the lower cross-bar 27. The side 85 legs 26 are longitudinally slotted as at 28 and nut and bolt combinations 29 carried by the legs 25 and extending through the slots 28 maintain the two U-shaped frame members in vertically adjusted position to accommodate mounting thereof on the back key stone 22. The lower cross bar 27 of the U-shaped frame member is mounted upon the arm 30 and is longitudinally adjustable 90 with respect to said arm by means of the 100

nut and bolt combinations 31 carried by the lower cross arm 27 and extending through the longitudinal slot 32 in the arm 30.

5 A tubular guide 33 extends between the side leg 26 of the U-shaped frame member in spaced relation to the lower cross bar 27 thereof and through which tubular guide, the damper operating rod 34 rectangular in cross section is freely mounted for rotation therein, the end of the damper operating rod 34 directed toward the key stone 23 being anchored in a bearing plug 35 that in turn is rotatably supported in the ornamental damper indicator plate 36 fixed to the upstanding bracket 37 rising from the adjacent end of the frame supporting rod 32. The damper operating lever 38 is fixed as at 39 upon the bearing plug 35 outwardly of the indicator plate 36. A tensioned stop ball 40 is carried by the damper operating lever 38 and is receivable in depressions 41 provided in the outer face of the damper indicator plate 36 as shown in Figure 6 for determining the angular or open and closed positions of the damper 18 relative to the flue 17, position indicating indicia 42 being denoted on the face of the damper indicator plate 36.

30 The connection between the damper operating rod 34 and damper 18 includes an arm 43 having a rectangular cross bore in one end thereof to receive the adjacent end of the damper operating rod 34 that is retained in position by means of the set screw 44. The outer end of the arm 43 carries an outwardly directed pin 45 upon which a relatively short tubular member 46 is pivotally mounted by means of diametrically opposite openings in said tubular member received on said pin with the tubular member retained in position on the pin by means of the collar pin 47 or other retaining element. As shown in Figure 7, a cylindrical plug 48 has a swivel connection with one end of the tubular member 46 by means of the inwardly directed flange 49 on the tubular member and the disk head 50 on the plug, the mounting of the tubular member 46 and plug 48 constituting a universal joint. The plug 48 is provided with a cross bore that receives one end of a link rod 51 to be anchored therein by the set screw 52 entering the outer end of the plug for engagement with the link rod 51 while the outer end of the link rod 51 is provided with a hook 53 engageable with an eye 54 carried by one side of the damper plate 18 as shown in Figure 1.

From the above detailed description of the device, it is believed that the construction and operation thereof will at once be apparent, it being noted that upon operation of the damper shifting lever 38, the damper operating rod 34 moves the arm 43 for the opening and closing of the damper 18 by

means of the link rod connection 51. The adjustable frame structure for the support of the damper operating mechanism permits proper positioning of the supporting frame upon various sizes of fire places and back 70 key stones while the universal connection within the operating mechanism permits the positioning of the damper 18 in a vertical flue 17 as shown in Figure 1 or in an angularly disposed flue 17a illustrated by dotted 75 lines in Figure 1 so that with the same operating mechanism and damper construction the apparatus may be mounted in fireplaces and associated flues of various designs.

In the form of invention illustrated in 80 Figures 2 and 3, the damper 18a carries bearing members 19a at opposite ends thereof for pivotal support in angle strip 20, the bearing members 19a having bores therein of rectangular form in cross section to receive one end of the damper operating shaft 34a that extends through an opening 55 in the front wall construction 11 of the fireplace above the mantel 13, the adjustable U-shaped frame members, both upright and 85 inverted being omitted in this installation 90 of the device and a support arm 30 alone employed for the mounting of the damper and operating shaft 34a. As shown in Figure 3, the damper operating rod 34a is retained in the bearing member 19a by means 95 of the set screw 56.

While there are herein shown and described the preferred embodiments of the invention, it is nevertheless to be understood 100 that minor changes may be made therein without departing from the spirit and scope of the invention as claimed.

I claim:

1. In a fireplace damper construction, a 105 key stone for the fireplace, a pivotally mounted damper and operating means therefor including an adjustable frame to accommodate mounting of the frame on key stones and fireplaces of different sizes, a 110 damper operating rod rotatably supported on the frame and a link rod between the operating rod and damper including a universal joint comprising an arm with the universal joint at the outer end of the arm and said link rod being adjustably positioned with respect to the universal joint.

2. In a fireplace damper construction, a 115 key stone for the fireplace, a pivotally mounted damper and operating means therefor including an adjustable frame to accommodate mounting of the frame on key stones and fireplaces of different sizes, a 120 damper operating rod rotatably supported in the frame and a link rod between the operating rod and damper including a universal joint, comprising an arm fixed to and radially projecting from the operating rod, a pin 125 projecting laterally of the outer end of the arm, a tubular member pivoted on the pin 130

with the longitudinal axis thereof extending transversely of the pin and a plug swivelled in the tubular member and to which the link rod is fixed.

5 3. In a fireplace damper construction, a key stone for the fire place, a pivotally mounted damper and operating means therefor including an adjustable frame to accommodate mounting of the frame on key stones
10 and fireplaces of different sizes, a damper operating rod rotatably supported on the frame and a link rod between the operating rod and damper including a universal joint, the adjustable frame including a pair of interfitting U-shaped members having the side legs thereof overlapped and means for holding the U-shaped members in adjusted positions.
15

20 4. In a fireplace damper construction, a
key stone for the fire place, a pivotally
mounted damper and operating means there-
for including an adjustable frame to accom-
modate mounting of the frame on key stones
25 and fireplaces of different sizes, a damper
operating rod rotatably supported in the
frame and a link rod between the operating
rod and damper including a universal
joint, comprising an arm fixed to and radi-
ally projecting from the operating rod, a
30 pin projecting laterally of the outer end of
the arm, a tubular member pivoted on the
pin with the longitudinal axis thereof ex-
tending transversely of the pin and a plug
swivelled in the tubular member and to
35 which the link rod is fixed, the adjustable
frame including a pair of interfitting U-
shaped members having the side legs there-
of overlapped and means for holding the U-
shaped members in adjusted positions.

40 5. In a fireplace damper construction, a
key stone for the fireplace, a pivotally
mounted damper and operating means there-
for including an adjustable frame to accom-
45 modate mounting of the frame on key stones
and fireplaces of different sizes, a damper
operating rod rotatably supported in the
frame and a link rod between the operating
rod and damper including a universal joint,
50 the adjustable frame including a pair of in-
terfitting U-shaped members having the side
legs thereof overlapped and means for hold-
ing the U-shaped members in adjusted pos-
55 tions, a bearing carried by one of the frame
members for the damper operating rod, an
arm adjustably attached to the adjustable
frame and supporting one end of the operat-
ing rod and a damper operating handle at-
60 tached to the last named end of the operat-
ing rod.

6. In a fireplace damper construction, a key stone for the fireplace, a pivotally mounted damper and operating means therefor including an adjustable frame to accommodate mounting of the frame on key stones and fireplaces of different sizes, a damper

operating rod rotatably supported in the frame and a link rod between the operating rod and damper including a universal joint, comprising an arm fixed to and radially projecting from the operating rod, a pin 70 projecting laterally of the outer end of the arm, a tubular member pivoted on the pin with the longitudinal axis thereof extending transversely of the pin and a plug swivelled in the tubular member and to which the link rod is fixed, the adjustable frame including a pair of interfitting U-shaped members 75 having the side legs thereof overlapped and means for holding the U-shaped members in adjusted positions, a bearing carried by one of the frame members for the damper operating rod, an arm adjustably attached to the adjustable frame and supporting one end of the operating rod and a damper operating handle attached to the last named end of the operating rod. 80 85 90

In testimony whereof I affix my signature.

JOSEPH KOBERLING.
